UNITED STATES PATENT OFFICE.

GEORGE A. AMSDEN, OF LITTLETON, AND ROTHESAY P. KIDDER, OF LOWELL, MASSACHUSETTS, ASSIGNEES TO THE LAMSON COMPANY, OF BOSTON, MASSACHUSETTS, A CORPORATION OF NEW JERSEY.

DROP-STATION FOR CABLE-CARRIER APPARATUS AND THE LIKE.

1,258,384.

Specification of Letters Patent.

Patented Mar. 5, 1918.

Application filed October 1, 1913. Serial No. 792,888.

To all whom it may concern:

Be it known that we, GEORGE A. AMSDEN and ROTHESAY P. KIDDER, citizens of the United States, respectively residing at Littleton, in the county of Middlesex and State of Massachusetts, and Lowell, in the county of Middlesex, and said State, have invented certain new and useful Improvements in Drop-Stations for Cable-Carrier Apparatus and the like, of which the following is a specification.

This invention relates to carrier despatch apparatus and more especially to cable carrier systems in general; the preferred construction hereinafter described exemplifying the invention as applied to a drop-station in what is known in the art as a high-line cable carrier system; the terms drop or drop-line station being used in this particular connection substantially in the sense in which this term is used in the granted patent to George A. Amsden Number 960,617, dated June 7, 1910.

In certain of its aspects therefore our present invention may be regarded as an improvement upon the so patented invention of said George A. Amsden; such improvement residing in part in the provision of a cross-over or means for bridging the depending delivery track, or its equivalent, whether said track be looped or otherwise, so as to permit carriers *en route* past a particular station to pass the station proper without passing directly therethrough; and furthermore, when desired, to pass said station in a substantially straight line devoid of pronounced bends, which latter obviously tend to cause rattle and noise of operation beside wear and tear upon the apparatus.

Another object of the invention is to enable the despatch of carriers from, for example, a clerk's station, which may or may not be of the cable drop-station type, with the practical certainty of non-interference with carriers passing said station and with a minimum of attention on the part of the operative or clerk.

We further aim to reduce moving parts to a minimum and in general to provide an apparatus so simple and effective in construction as to be able to efficiently meet the exacting requirements to which, for example, store service apparatus is subject.

These and other objects of our invention will be hereinafter referred to and the novel elements and combination of elements whereby said objects may be obtained will be more particularly set forth in the claims appended hereto.

In the accompanying drawings which form a part hereof and in which like reference characters designate like parts, we have exemplified a cable system drop-station in which are embodied preferred forms of the essential, together with certain relatively non-essential but useful features of our invention; but we are aware of various changes and modifications which may be made herein, and of various other applications and embodiments of our invention in cable and other carrier despatch systems and hence do not desire to be limited in any way other than by the scope of said claims as applied to what may properly be termed carrier systems in general, the term carrier systems obviously not being intended to apply to passenger railways and the like, but being used in the sense in which this term is commonly used in this art.

Referring to the drawings:

Fig. 1 is a front elevation of the preferred drop-station above referred to.

Fig. 2 is a side elevation of the same, drawn to an enlarged scale; the apparatus shown in Fig. 1 being viewed from the right.

Fig. 3 is a detail rear elevation of the lower portion of the drop station or, in other words, of the station proper; a portion of the apparatus being broken away.

Fig. 4 is a detail of the grip opening and grip closing cams located at the left of the station proper, as viewed in Fig. 3.

Fig. 5 is a top or plan view of the improved cross-over drop-station.

Fig. 6 is a detail rear elevation of the upper portion of the drop-station.

Fig. 7 is a perspective detail view of one of the bridge elements in the main track; and

Fig. 8 is a detail section of said element together with certain of its associated parts; the section being taken on the line VIII—VIII of Fig. 6.

Referring first to Fig. 1, the main tracks, it will be here observed, are both preferably so disposed as to convey the carrier with its

grip pointing down; and the outgoing track from the cashier's station, not shown, has been designated 1 and of course constitutes the delivery track to the way stations, while 5 the incoming track 2 to said cashier's station constitutes the receiving track for said way stations.

In the preferred form of our invention but a single endless cable 3 is provided which 10 constitutes the means for elevating carriers from the way station or stations to the main receiving track 2; this cable being looped down through the station in much the same manner as is that shown in said Patent No. 15 960,617.

We do not desire, however, to be limited in any way to a single endless cable except where in certain of the claims such construction is specifically referred to, since it 20 is obvious that other means may be employed for elevating or otherwise moving the carrier from the clerk's station to the main track. We regard it as preferable, however, to employ but a single endless looped cable owing to the simplicity of construction which is rendered possible by the 25 use of this propelling device.

The cable 3 propels the carriers along the main tracks in the directions of the arrows 30 indicated adjacent thereto and the cable of the receiving track passes downwardly around the idler 4 to the pulley or idler 5 and thence up around the idler 6 and on to the next way station or to the cashier's station as the case may be.

The idlers 4 and 6 are suitably journaled in brackets 7-8 and the idler 5 is mounted in a casing which preferably completely encloses the same and thereby avoids possible 40 injury to the person or garments of an operator.

As shown in Fig. 3, casing 9 is rigidly mounted upon an upright 10 and has laterally outstanding therefrom the brackets 11 45 and 12 to which are affixed the respective sides of the lower looped portion 13 of an independent track 14 which delivers carriers to the station from a switch 15; the latter being adapted in a known manner to selectively remove carriers from the track 1 50 which are destined for a given or predetermined station.

The construction of the switch 15 is, it 55 may be here noted, substantially the same as that of the corresponding part in said Patent No. 960,617 as indeed is also the general arrangement of the independent track 14, save for certain features of relatively minor importance as compared with the 60 proved operation of the system as a whole. It may be noted in connection with the independent track, however, that provision is made for the removal of a carrier from either side of the loop in the bottom thereof; 65 since carriers may be drawn upwardly and

out of engagement with said track at the extremity 16 thereof while they may also be removed through the aperture 17 provided therein upwardly to the right of casing 9 as in Fig. 3.

The descending limb of the loop in the cable passes through a tube 18 which protects the cable from possible injury at the station; the lower end of said tube being preferably sweated into the casing 9, as indicated.

A delivery track or guide 19 extends up from the opposite side of casing 9 substantially to the receiving track 2; a gap in the latter, normally closed by a bridge or bridge 80 elements 20, serving to permit of the passage of a carrier from the delivery track to said receiving track.

The bridge preferably consists of two oppositely movable elements 20, which are respectively hinged at 21 as shown in Figs. 5, 6 and 8; each element 20 being of sheet metal, the longitudinal edges of which are curled and cut away as indicated in Fig. 7.

The curled outer edge of each bridge element is centrally recessed as at 22 for the reception of a coil spring 23, one end of which is in engagement with a suitable fixed point, e. g. on the corresponding hinge pin 21, and the other end 24 of which bears against said element, so that each of the latter normally tends to move toward the position in which it is shown in Figs. 5 and 6, and in which one of these elements is shown in Fig. 8.

The ascending carrier swings upwardly and apart the bridge elements; outward movement of the latter being limited by suitable stops 25 which extend upwardly from the respective brackets 26 through ears 95 of which are driven the hinge pins 21. The tips 25' of the stops may, if desired, be made of soft rubber to reduce noise.

Preferably also these stops are adapted to hold the elements 20 at the limit of their outward travel in such manner that gravity will aid the return of the latter to their horizontal positions if at any time the corresponding spring 23 should become ineffective; although the rebound from stops 25, 115 when the bridge members are driven thereagainst also tends to return said elements to their normal positions.

The inner edges of the plate-like elements 20 are curled into conformity with the diameter of the preferably round rods which constitute the track, and the ends of these curled edges, or corners of the plates, are cut away below to provide for proper engagement of the upper sides thereof with the reduced 125 ends 27-27' of the track members or rods 2 (see Figs. 6 and 7); the end 27' also being sloped upwardly to facilitate the emplacement of the carrier on the receiving track.

As shown in Fig. 6, sufficient clearance 130

is provided between the upper ends of the track members 19 and the reduced ends 27' of track 2, to permit of the free passage therebetween of the retaining lugs C' or 5 like parts common to carriers 29 adapted for use in systems of this character (for a more complete description of such carriers see Patent No. 960,617, which shows the lugs in question together with the carrier grip 10 construction hereinafter referred to). Obviously, when the bridge is in its closed or normal position a through carrier 29 *en route* along track 2 past the station shown will traverse the gap in engagement with the 15 inner curled edges of the elements 20, while a carrier being delivered from the station to said track will lift the bridge and jump the clearance spaces 28.

Track 19 is preferably bent inwardly 20 somewhat, as at 31, to facilitate the emplacement thereon of the carriers being despatched; the track members being preferably spread to provide the usual carrier-lug receiving apertures 32. Above the apertures, or as we may term it in conformity 25 with the usage in the art, aperture 32, is a bracket 33 which carries a carrier grip opening cam 34 and a grip closing cam 35.

The purpose of the cam 34 is to open the 30 grip of a carrier which is being despatched if said grip has inadvertently become closed, thereby relieving the operative of the necessity for inspecting the grip before attempting to despatch a carrier; this resulting in a 35 saving of time and rendering the apparatus even in this particular substantially automatic in character. Although grip opening cams have been known in the art, they have, to the best of our knowledge, never been 40 applied to drop stations in operative relationship to the carrier admitting aperture for the purposes in question.

The cam 35 is substantially immediately 45 above the grip opening cam and serves to close the grip upon the cable as the carrier is raised by the hand of the operative.

Above the bracket 33 is a second bracket 36 which carries a cam 37, the purpose of 50 which will be hereinafter mentioned; while a determined distance above cam 37 is a movable grip-opening cam 38 which is movable into and out of its operative position by means of the following mechanism:

To the left of Fig. 1 and right of Fig. 2 55 is a rod or strip 39 which, together with its suspending arms 40, constitutes an actuating frame or member for said cam 38.

The arms 40 are fixedly mounted upon a 60 rock shaft 41 journaled in brackets 42-43-44-45, and carrying an arm 46 which, when said shaft is rotated counter-clockwise, as viewed in Fig. 2, raises, and lifts a bent link 47 which in turn lifts the crank arm 48, controlling the cam 38, and thereby 65 swinging the toe of said cam into its dotted

line position shown in Fig. 2. When so disposed cam 38 is adapted to push open the pivoted grip element of the carrier ascending from the station, which frees the carrier from the cable with which it had 70 been in engagement and permits it to drop back by gravity until said grip element encounters the downwardly sloping upper or operative surface of the cam 37, whereupon the carrier grip reengages the cable and the 75 carrier again travels upwardly toward the receiving track 2. As long as cam 38 occupies its inner or operative position, so long will the carrier being despatched reciprocate to and fro along track 19, the 80 action being entirely automatic and the operative having practically no need to pay further attention to the despatched carrier once he has engaged it with this track and lifted sufficiently to cause its grip to be engaged with the cable through the instrumentality of cam 35. As soon as cam 38 moves out of the path of the carrier the latter immediately passes upwardly onto track 2 and pursues its journey. 85

The frame which actuates cam 38 in manner aforesaid is controlled by the carriers traversing the main track 2 past the station; bar 39 being normally held in the path of these carriers both by gravity and by a 90 helical spring 49 suitably connected at one end to the bracket 43 and at the other to a collar 50 upon the rock shaft. The right-hand extremity 39' of rod 39, as viewed in Figs. 5 and 6, is outwardly curved so that 95 an approaching carrier may wipe this rod aside and thereby swing cam 38 into its operative position as above described and as long as said carrier is in contact with rod 39, cam 38 will prevent the delivery of any 100 carrier being despatched from the way station to the main track. 105

This apparatus precludes the possibility of a collision between these two carriers while of course the engagement of the 110 through carrier is scarcely more than momentary and the retention of the carrier being despatched upon its track 19 normally occasions no material loss of time.

The rod 39 is, however, of sufficient length 115 and is so disposed as to insure the stoppage of the ascending carrier regardless of the relative remoteness or nearness of the through carrier to the clearance space 28 so long as there would otherwise be any 120 possibility of a collision between the two.

The fact, however, that the carrier despatched from the station requires no more attention, whether it be held up by the passage of a through carrier past the station 125 or not, is obviously of great importance, while the fact that collisions are absolutely prevented is of even greater importance since the operation of the whole system would be apt to be affected and the appa- 130

ratus possibly damaged by the occurrence of a collision at or adjacent the bridged gap.

Experiment has demonstrated the advantage of having the cam 38 rock or otherwise move in substantially the plane in which moves the pivoted grip element of the ascending carrier, rather than to move at right angles to said plane, since play must be provided between the carrier and the rails or rods upon which it travels, and a rounding of the top of cam 38, such as is apt to result from wear in time, may permit the pivoted grip to slip past the cam and reengage the cable, whereas when this cam is mounted for movement as shown the pivoted grip as it opens moves more fully into engagement with the cam and any ordinary wear at the toe of the latter becomes practically unimportant and negligible.

The bracket 43 carries a grip opening cam 51, the function of which is to free a through carrier from the cable before the portion of the latter with which the carrier grip is in engagement passes down over the idler 4. The momentum of the carrier then carries it over the bridge and onto the section of track 2 therebeyond.

As shown in Fig. 6, a slight depression or dip 52 is provided in this section immediately beyond the extremity 27' thereof, the purpose of which is to lower the carrier momentarily toward the cable; the open jaws of the grip straddling the latter.

At substantially the lowermost point of this slight drop is a grip closing cam 53 which, as the pivoted jaw of the grip rides therealong, closes the latter in a known manner so that the carrier is thence propelled along the main track by the cable.

Cam 51 of course only unlocks the grips of through carriers.

We particularly desire to direct attention to the fact that the through track 2, as well as the track 1, has the rails thereof so disposed as to convey carriers with their covers up or, in other words, with the carriers horizontally disposed rather than edgewise as in the preceding system described in Patent 960,617, so as to reduce the chance, in the event of the covers becoming inadvertently opened while the carriers are in transit, of spilling their contents, while further the weight of the carrier and wear is distributed upon both rails rather than one, and the necessity for special bends in the tracks for turning the carrier through 90 degrees about its longitudinal axis, frequently encountered in practice in said former system is practically eliminated. This delivery of the carriers from the way station to the main track 2, in a manner which we may term flat-wise in contradistinction to edge-wise, is hence of very great importance from a practical and

commercial standpoint and is something which has heretofore not been done, to the best of our knowledge, in drop-station construction.

The bridge construction shown in the preferred embodiment of our invention is especially well adapted to a system of this description although we do not desire to be limited thereto except where specifically claimed. The provision of a pivoted bridge, such as shown, wherein the axis of rotation of a movable bridge element is substantially parallel to the track, and especially where two such elements or a two-part bridge is utilized, results in permitting the use of bridge members of light construction and moreover members no part of which is very remote from the pivotal axis, which hence for two reasons reduces the effect of inertia and thereby facilitates a rapid and easy opening and closing of the bridge, preferably by the ascending carrier itself.

The drop of a carrier which is stopped by cam 38 and thereupon falls into operative engagement with cam 37, may in some cases be made as small as three inches, that is, a three inch drop will suffice to close the grip of a carrier the pivoted grip element of which is not too stiff. In practice, however, we prefer to allow a greater fall in order to obviate excessive reciprocation of the carrier on track 19. If cam 37 be omitted, obviously the upper side of cam 35 may be made to act as the reengaging cam, and where the station is relatively adjacent the main tracks, or in other words, when the total drop is not great, cam 35 may be so employed.

Carriers being delivered to the station via track 1 are selectively removed from the latter through the aperture 54, the switch 15 engaging the usual switch guides C² upon the carrier which are preferably set up above the level of the lugs C⁷ some determined distance corresponding to the particular station at which they are to be delivered, in a known manner.

The carrier selected for delivery is propelled up the switch rails by the cable and is then disengaged from the latter by the grip opening cam 55 which pushes or wipes open the pivoted grip jaw and frees the cable; a cord or cable releasing bracket 56 supported from the rails 14 aiding in freeing the cable from engagement with the grip in a known manner.

No claim is made to the particular manner in which the rails are recessed or indented adjacent the carrier receiving or releasing apertures therein, such indentation being commonly provided to facilitate the entrance or emergence, as the case may be, of the carrier lugs C⁷.

The mode of operation of the apparatus

given by way of exemplification is as follows:—

Assuming first that the carrier 30 is *en route* past the station shown with its grip 5 in engagement with the cable 3.

Upon encountering cam 51, the grip is swung open and the cable drops down; the previously engaged portion passing down through the loop and the carrier proceeding 10 along track 2 and over the closed bridge by momentum.

It then passes on over the further section of track and dips down until its grip can be reengaged by cam 53 with the cable, after 15 which it is propelled on to the next way station where the successive disengagement and reengagement of the cable is again effected, and so on until it is delivered, let us say, to the cashier.

20 As each way station is passed the through carrier swings aside the movable cam actuating-frame thereof, which promptly resumes its position in the path of succeeding carriers as soon as the passing carrier permits 25 it to.

If now a carrier be despatched from the way station shown, while cam 38 is held in its operative position by a passing through carrier, so that its grip encounters cam 38 30 before the latter moves away from the cable, the despatched carrier will be freed from the cable and will fall by gravity until its grip is reclosed by cam 37. The cable then re-lifts this carrier and unless a second 35 through carrier should chance to be immediately behind the first, the despatched carrier will normally have an opportunity, after this one reciprocation thereof, to emerge onto the main track through or past 40 the bridge, said carrier swinging apart the elements 20 in so doing and the latter immediately thereafter moving back to their closed or normal positions.

If a second through carrier closely succeed the first, the despatched carrier may 45 again be forced to reciprocate along its track 19 and it will continue automatically so to do until service conditions permit of unimpeded delivery, whereupon it will be delivered to track 2 by the action of the propelling cable; being subject to the propulsive effort of the latter even while passing by or through the bridge.

A carrier *en route* along track 1 and intended for the station shown will be selectively removed from said track by the switch, its grip will be opened by cam 55 and the cable will be removed therefrom by gravity and by the action of bracket 56, 50 the carrier then descending track 14 and coming to rest in the loop 13 of the latter, whence it may be removed either backwardly through aperture 17, or forwardly from the rail extremities 16.

A carrier being despatched from the station will, in manner aforesaid, have its grip unfailingly opened by cam 34, if it be not already open, and the cam 35 will operatively engage said grip with the cable as the carrier is raised by the hand of the operator. 65 70

The system is hence practically automatic throughout, the only manual operations required, in so far as the sending or receiving of a carrier is concerned, being the insertion and initial lifting of the carrier and the 75 removal of the carriers arriving at the station; while together with this unfailing automatic operation, insurance against collision of carriers is provided.

We particularly direct attention to the 80 fact that while the apparatus shown is of the drop-station type nevertheless the track-way for through carriers is practically free from any pronounced bends which would cause rattle and noise and result in wear and 85 tear on the apparatus.

The small number of idlers or pulleys, *i. e.*, three, should also be observed, since the arrangement of the apparatus with this number while permitting a continuously operated cable to move past or through the station, also permits of the maintenance of the 90 number and sharpness of the bends in this cable at a minimum; the said arrangement further being particularly well adapted to 95 co-act with the cross-over provisions which permit of the direct line travel of through carriers, especially when said carriers are traveling flatwise.

To the best of our knowledge it has never 100 heretofore been attempted to provide means for operatively connecting the grip of an out-bound carrier with the flexible hoisting element or cable, by a free drop of said carrier.

This means, further, in combination with the normally inoperative means for disconnecting the carrier from the hoisting element 105 permits, it will be noted, of the automatic checking of the progress of the carrier while yet permitting further movement thereof, *i. e.*, downwardly while the carrier is normally caused to resume its journey after the lapse of a usually slight but nevertheless substantially predetermined period of time. 110 115

The releasing and engaging members or cams 38 and 35 act substantially independently of each other; not being operatively connected other than by the auxiliary track.

It has further, to our knowledge, never 120 been attempted to deliver carriers to a main track through a vertically opening gap in said track, by propelling said carriers up from a drop-station by power driven means.

Finally the advantageous disposition of 125 the auxiliary and independent up-looped tracks with respect to each other and to the cable and the idler located at the sta-

tion should be noted, since by reason of this arrangement a material economy of space is effected and the station rendered most sightly.

5 Having thus described our invention what we claim is:—

1. In cable carrier despatch apparatus, a main track, a station, carriers, means, including a continuously driven cable running 10 in adjacency to a part of said station, for conveying carriers from said station to, and thereafter propelling said carriers along, said main track, said carriers having parts whereby they may engage said cable to be 15 thereby conveyed toward said main track, and mechanism for preventing collisions involving a carrier despatched from said station and a carrier *en route* over said main track past said station, said mechanism including a device located along the path of travel of one of said carriers and adapted to be operatively disposed in said path to engage and check the progress of a carrier rapidly moving along said path, and means 20 automatically controlled by the other of said carriers for actuating said device.

2. In carrier despatch apparatus, a main track, a station, carriers, an auxiliary track leading from said station to a point in said 30 main track, a bridge in one of said tracks, disposed substantially at said point and means, including a cable which extends in adjacency to a part of said station, for conveying carriers from said station to, and thereafter propelling said carriers along said main track, said carriers having parts normally operatively in engagement with said 35 cable when being conveyed thereby toward said main track and out of operative engagement with said cable when traversing said bridge.

3. In carrier despatch apparatus, a main track, a station, an auxiliary track leading from said station to said main track, a 45 bridge in one of said tracks, and power driven means for conveying carriers from said station to, and thereafter propelling said carriers along, said main track, said bridge having a tendency for a determined 50 position and being normally movable out of said position only by a carrier traversing one of said tracks.

4. In a cable carrier system, a main track having the rails thereof disposed in the 55 same horizontal plane to support carriers horizontally thereon, a way station below said main track, an auxiliary track directly engaged by carriers traveling from said station to said main track, and power actuated 60 means, including a continuously driven cable, for conveying carriers up from said station to and thereafter propelling said carriers along, said main track, said auxiliary track having the rails thereof disposed to deliver carriers to said main track 65

in their horizontal position, and cross-over means co-acting with said main track for guiding carriers, *en route* along said main track past said station, over said station out of engagement with said auxiliary track.

5. In a cable carrier system, a main track, means, including a cable, for propelling carriers along said track and for delivering an out-bound carrier to said track at a predetermined point therein, means, operable, in part at least, by a second carrier *en route* over said track past said point, for temporarily stopping said out-bound carrier, and means operating substantially with certainty to positively and automatically re-despatch 70 said out-bound carrier thereafter.

6. Cable carrier despatch apparatus comprising a main track, a station, an auxiliary track leading from said station substantially to a point in said main track, a bridge in one of said tracks disposed substantially at said point, the track in which is disposed said bridge comprising a plurality of rails having gaps therein and said bridge adapted to complete said plurality 90 of rails across said gaps, and means, including a cable, for conveying carriers from said station to, and thereafter propelling said carriers along said main track, parts of said bridge being mounted for movement in a substantially vertical plane and said station being in a different plane, horizontally, from that of said main track at 95 said point.

7. Cable carrier despatch apparatus comprising a main track, a station, an auxiliary track leading from said station substantially to a point in said main track, a bridge in one of said tracks disposed substantially at said point, and movable into 100 an inoperative position to permit the passage of a carrier thereby, and means, including a cable, for conveying carriers from said station to, and thereafter propelling said carriers along said track, said means adapted to exercise a substantially continuous propulsive effort upon said carrier while the latter is passing by said bridge when the bridge is inoperatively disposed.

8. Carrier despatch apparatus comprising a main track, an auxiliary track adapted to deliver carriers thereto, power driven means for propelling carriers along said tracks, means for stopping the forward movement of a carrier *en route* along said auxiliary track at a determined point therein whenever normal service conditions in said main track fail to permit of an unimpeded delivery of said carrier thereto, and means co-acting with said power driven means for thereafter automatically and surely delivering said carrier to said main track when such unimpeded delivery is 115 possible.

9. Carrier despatch apparatus comprising 130

- ing a main track, an auxiliary track adapted to deliver carriers thereto, a carrier adapted for direct operative engagement successively with said tracks, power driven 5 means for propelling said carrier successively along said tracks, and means for stopping the forward movement of a carrier *en route* along said auxiliary track at a predetermined point and for substantially 10 freeing said carrier from the power driven means whenever normal service conditions in said main track fail to permit of an unimpeded delivery of said carrier thereto.
10. In carrier despatch apparatus, a main 15 track, an auxiliary track adapted to deliver carriers thereto, and means for causing a despatched carrier about to be delivered from said auxiliary track to said main track to automatically reciprocate to and fro upon 20 said auxiliary track until service conditions upon said main track permit of proper delivery of said carrier thereto.
11. In cable carrier despatch apparatus, a main track, a station out of the line of 25 said track, an endless cable for propelling carriers along said track, said cable being looped away from said track toward and through said station, guides co-acting with the looped portion of said cable to deliver 30 carriers from said station to said track, and provisions whereby carriers *en route* along said track past said station may pass by the latter substantially regardless of the loop in said cable.
- 35 12. In cable carrier despatch apparatus, a main track, a drop station, an endless cable for propelling carriers along said track, said cable being looped down from said track at said drop-station, means co-acting with the 40 looped portion of said cable to deliver carriers from said station up to said track, and cross-over and operative provisions whereby carriers *en route* along said track past said 45 station may pass by the latter substantially regardless of the loop in said cable.
13. In cable carrier despatch apparatus, a main track, a station out of the line of said track, a cable for propelling carriers along said track, said cable being looped away 50 from said track toward and through said station, carriers having provisions for engaging said cable, guides co-acting with the looped portion of said cable to deliver carriers from said station to said track, means 55 for disengaging carriers *en route* along said main track past said station from said cable substantially upon arriving at the loop therein, and means for automatically reengaging said carriers with said cable after 60 passing said loop.
14. A cable carrier despatch apparatus having a drop-station, said apparatus comprising a receiving track to convey carriers horizontally flat-wise and at a substantially 65 constant level over said drop-station, said track having a gap therein through which carriers despatched from said drop-station enter said receiving track horizontally flat-wise, power driven traction means for propelling a carrier from said station up to said 70 track, and guides to deliver said carrier through said gap horizontally flat-wise to said track.
15. A cable carrier despatch apparatus having a drop-station, said apparatus comprising a receiving track to convey carriers horizontally flat-wise thereover past said drop-station, said track having a substantially vertically opening gap therein, power driven traction means for propelling a carrier from said station up to said track, and guides to deliver said carrier up through 75 said gap to said track.
16. A cable carrier despatch apparatus having a drop-station, said apparatus comprising a track to convey carriers horizontally flat-wise thereover past said drop-station, said track having a substantially vertically opening gap therein, power driven traction means for propelling a carrier from 80 said station up to said track, guides to deliver said carriers up through said gap to said track and means for bridging said gap for said first mentioned carriers.
17. A cable carrier despatch apparatus having a drop-station, said apparatus comprising a multiple-rail receiving track to support carriers traversing the track over said station horizontally flat-wise while so doing, said track having a gap therein in 85 two of the rails thereof, and means including a continuously driven cable, for elevating a carrier from the station through said gap to said track.
18. A cable carrier despatch apparatus having a drop-station, said apparatus comprising a multiple-rail receiving track to support carriers traversing the track over said station horizontally flat-wise while so doing, said track having a gap therein in two of 90 the rails thereof, means including a continuously driven cable, for elevating a carrier from the station through said gap to said track and means for bridging said gap for carriers passing said station.
19. A cable carrier despatch apparatus having a way station, said apparatus comprising a multiple-rail receiving track extending past said station and being free from pronounced bends at said station, said 100 track having the rails thereof disposed to convey carriers horizontally flat-wise over said station, said track having a gap therein in two of the rails thereof, and means including a continuously driven cable for propelling carriers from said station through said gap.
20. A cable carrier despatch apparatus having a way station, said apparatus comprising a multiple-rail track extending past 105

said station, said track having a gap therein in two of the rails thereof and being free from pronounced bends in the immediate vicinity of said station, and means including a continuously driven cable for propelling carriers from said station through said gap.

21. A cable carrier despatch apparatus, having a drop-station, said apparatus comprising a track, the rails of which lie in substantially the same horizontal plane, to convey carriers horizontally flat-wise there-over past the station proper, said station being materially below the level of said track adjacent said station, continuously operating means for propelling a carrier from the station up to said track, and guides curved around in parallel and substantially vertical planes from below said rails and toward the under sides of the latter to deliver said carrier substantially horizontally flat-wise to said track.

22. A cable carrier despatch apparatus having a drop-station, said apparatus comprising a track, the rails of which lie in substantially the same horizontal plane, to convey carriers horizontally flat-wise there-over past said drop-station, a flexible hoisting element for propelling a carrier in operative relationship therewith from the station up to said track, and guides curved around in parallel and substantially vertical planes from below said rails and toward the under sides of the latter to deliver said carrier substantially horizontally flat-wise to said track.

23. A cable carrier despatch apparatus having a drop-station, said apparatus comprising a track, the rails of which lie in substantially the same horizontal plane, to convey carriers horizontally flat-wise there-over past said drop-station, a flexible hoisting element for propelling a carrier from the station up to said track, and guides curved around in parallel and substantially vertical planes from below said rails and toward the under sides of the latter to deliver said carrier substantially horizontally flat-wise to said track, said flexible element moving in substantially the path of said last mentioned carrier when delivering said carrier.

24. Cable carrier despatch apparatus comprising a track, a cable for propelling carriers therealong, a carrier adapted to traverse said track and provided with a grip for operatively engaging said cable, a member relatively movable into the path of said carrier for freeing said cable from said grip, a second track, one of said tracks being disposed for delivery of carriers to the other, and means controlled by a carrier traveling along said second track for moving said member into the path of the carrier traversing said first track.

25. Cable carrier despatch apparatus comprising a track, a cable for propelling carriers therealong, a carrier adapted to traverse said track and provided with a grip for operatively engaging said cable, a device for freeing said cable from said grip, a second track, one of said tracks being disposed for delivery of carriers to the other, and means, controlled by a carrier traveling along said second track for actuating said device to disengage a carrier traversing said first track from said cable.

26. Cable carrier despatch apparatus comprising a first track, a second track adapted to direct carriers toward said first track, a flexible element for propelling carriers along at least one of said tracks, carriers provided with parts adapted for operative engagement with said flexible element, whereby to propel said carriers, and means controlled by a carrier traversing one of said tracks for disengaging a carrier traversing the other of said tracks from said flexible element.

27. A cable carrier way drop-station having an upwardly extending multiple-rail carrier despatching track and a pulley adjacent the lower end of and to one side of said track, in combination with a cable and a carrier having means for engaging said cable when operatively disposed upon the rails of said track, said track having an opening therein for the operative insertion of a part of said carrier from the side of said track which is directed toward said pulley, and means upon the opposite side of said track for engaging the cable engaging means of said carrier with said cable, the plane of said despatching track being substantially parallel to the axis of said pulley.

28. A cable carrier way drop-station having an upwardly extending multiple-rail carrier despatching track and a pulley adjacent the lower end of and to one side of said track, in combination with a cable and a carrier having means for engaging said cable when operatively disposed upon the rails of said track, said track having an opening therein for the operative insertion of a part of said carrier from the side of said track which is directed toward said pulley, and means upon the opposite side of said track for engaging the cable engaging means of said carrier with said cable, and a second pulley adjacent the upper end of said track and around which passes said cable, said second pulley being upon the same side of said track as said last mentioned means and said cable being adapted to draw said carrier horizontally flat-wise around said second pulley.

29. In cable carrier apparatus, a main track, a cable running in a determined direction substantially parallel to said main track for propelling carriers therealong, and a drop-station intermediate the ends of said

main track having an ascending auxiliary track to deliver carriers horizontally flat-wise to said main track, said auxiliary track having an opening therein for the operative 5 insertion of a part of a carrier from the side of the track which faces substantially opposite the said determined direction.

30. A cable carrier apparatus comprising a receiving and a delivery track, an independent track adapted to receive carriers from said delivery track, means for selectively delivering carriers, traversing said delivery track, to said independent track, an auxiliary track adapted to deliver carriers to said 10 receiving track, power means for propelling carriers along some of said tracks, and means for subjecting a carrier downwardly traversing a part at least of one of said tracks, to the action of said power means by the 15 substantially unaided action of gravity upon 20 said carrier alone.

31. A cable carrier apparatus comprising a receiving and a delivery track, an independent track adapted to receive carriers from said delivery track, means for selectively delivering carriers, traversing said delivery track, to said independent track, an auxiliary track adapted to deliver carriers to said receiving track, power means for propelling carriers along some of said tracks, and means for subjecting a carrier downwardly traversing a part at least of one of said tracks, to the action of said power means by the substantially unaided action of 25 gravity upon said carrier alone to thereby 30 reversely actuate said carrier by said means.

32. A cable carrier apparatus comprising a way, a portion at least of which is set at an angle departing widely from a horizontal 40 plane, a cable, a carrier having a grip for engaging said cable, and means for operatively connecting said grip with said cable by a free drop of said carrier abruptly downward along said way under the action 45 of gravity.

33. A cable carrier apparatus comprising a way, a portion at least of which is set at an angle departing widely from a horizontal plane, a cable, a carrier having a grip for 50 engaging said cable, and means for operatively connecting said grip with said cable by a downward movement of said carrier along said portion of said way, said cable moving in substantially a reverse direction 55 to that taken by the carrier when moving downwardly along said way.

34. A cable carrier apparatus comprising a cable, a drop-station having a pulley around which passes said cable substantially 60 at the station proper, main tracks, one having a gap therein, for receiving carriers from said drop-station and the other for delivering carriers to said drop-station, said drop-station having an auxiliary track adjacent 65 said cable for delivering carriers to said re-

ceiving main track and having also means including an independent track for selectively receiving carriers from said delivery main track, said independent track extending downwardly from said delivery main track 70 and being looped directly around and in the plane of said pulley, and means to bridge said gap for the conveyance therewith of carriers *en route* over said station along said receiving main track. 75

35. A cable carrier apparatus comprising a cable, a station having a pulley around which passes said cable, main tracks above the level of said station, one of which receives carriers from said station and the 80 other of which delivers carriers toward said station, means including an independent track adapted to selectively receive carriers from said delivering main track, and an auxiliary track comprising two rails curved 85 around in parallel and substantially vertical planes from below said receiving main track and directly toward the under side of the latter for delivering carriers from said station substantially horizontally flat-wise to 90 said receiving main track.

36. A cable carrier apparatus comprising a cable, a station having a pulley around which passes said cable, main tracks above the level of said station, one of which receives carriers substantially horizontally flat-wise from said station and the other of which delivers carriers toward said station, means including an independent track 95 adapted to selectively receive carriers from said delivering main track, and an auxiliary track to deliver carriers from said station substantially horizontally flat-wise to said receiving main track, the plane of said auxiliary track being substantially parallel to 100 that of said independent track and both of said planes intersecting the plane of said receiving main track.

37. In cable carrier apparatus, a main track, an auxiliary track adapted to deliver 110 carriers to said main track, a cable for propelling carriers along said auxiliary track, and means mounted for movement into and out of the path of a carrier traversing said auxiliary track, for disengaging said carrier 115 from said cable.

38. In cable carrier apparatus, a track, a cable for propelling carriers over said track, a carrier having a part for engaging said cable, means for stopping said carrier *en route* over said track and disengaging it 120 from said cable in accordance with service conditions in said apparatus, and means for thereafter automatically reengaging said part with said cable by the action of gravity when said conditions permit. 125

39. In cable carrier apparatus, a track, a cable, a carrier adapted for operative engagement with said cable, movably mounted means for disengaging said carrier from said 130

cable and means, rendered operative by the action of gravity upon said carrier, for engaging said carrier with said cable.

40. In cable carrier apparatus, a track, a cable, a carrier adapted for operative engagement with said cable, movably mounted means for disengaging said carrier from said cable and means, rendered operative by the action of gravity, for engaging said carrier with said cable.

41. In cable carrier apparatus, a track, a cable, a carrier adapted for operative engagement with said cable, means for disengaging said cable from said carrier, means for engaging said cable and carrier thereafter within a substantially predetermined time, one of said means being movably mounted, and mechanism for actuating said movably mounted means.

42. In cable carrier apparatus, a track, a cable, a carrier adapted for operative engagement with said cable, means for disengaging said cable from said carrier, means for engaging said cable and carrier thereafter within a substantially predetermined time, one of said means being movably mounted and said means being substantially independent of each other in their respective actions, and mechanism for actuating said movably mounted means.

43. A cable carrier despatch apparatus comprising a way, a cable for propelling carriers along said way, automatic means for checking a carrier in operative engagement with said cable at a determined point in said way while permitting a further movement of said carrier, and means for automatically causing said carrier to resume its progress along said way by the propulsive action of said cable at substantially full speed.

44. A cable carrier despatch apparatus comprising a way, a cable for propelling carriers along said way, a carrier in operative engagement with said cable, and automatic means for causing a reversal of the direction of travel of said carrier along said way, whereby to return said carrier to a point in said way from which it may be redespached, and means for despatching said carrier from said point.

45. A cable carrier drop-station, continuously driven means for despatching carriers from said station to said track, and means for preventing collisions involving carriers being despatched from said drop-station and carriers traversing said main track, said means having provisions for releasing the carrier being despatched thereby from the action thereof.

46. The combination of a main track with a cable carrier drop-station, continuously driven means for despatching carriers from said station to said track, normally inoperative means adapted, when operative, to prevent the despatch of a carrier to said track by said continuously driven means, and means for rendering said means operative.

47. The combination of a main track with a cable carrier drop-station, said track having cross-over provisions at said station, and a cable running through said station to propel a carrier up to and thereafter along said main track.

48. In a cable carrier despatch apparatus, a main track, an auxiliary track adapted to guide carriers up from a station at a lower level than said main track unto the latter, said main track having a gap therein through which carriers from said station are introduced and having movable means for substantially bridging said gap whereby carriers traversing said main track past said station may ride safely past said gap, and power means, including a cable, for positively propelling carriers along said main and auxiliary tracks, said bridging means being movable to its gap uncovering position by a carrier traversing said auxiliary track.

49. Cable carrier apparatus comprising a track, a station, an auxiliary way leading up from said station substantially to a point in said track, means, including a cable, for propelling carriers along said track and up said auxiliary way, carriers having means for operatively engaging said cable, and means for engaging the said last mentioned means with said cable when said carrier has dropped at least a determined distance along said way under the action of gravity.

50. In cable carrier apparatus, a main track, an auxiliary track adapted to deliver carriers to said main track, a cable for propelling carriers along said auxiliary track, means, a relative movement between which and the path of travel of a carrier traversing said auxiliary track, effects a disengagement of said carrier from said cable when said carrier encounters said means, and mechanism for effecting said relative movement between said means and the path.

51. In cable carrier apparatus, carriers, despatching and receiving main tracks having stations therealong at a lower level than said main tracks, drop tracks leading down from said despatching main track to said stations, auxiliary tracks leading up from said stations to said main receiving track, means, including a continuously driven cable, for propelling carriers up said auxiliary tracks and along said main tracks, parts of said means extending down at each station in adjacency to said auxiliary tracks, switching devices to selectively remove carriers from said despatching main track and deliver them to said drop tracks in accordance with the station to which said carriers be-

long, said carriers each having auxiliary-track engaging lugs, a grip to engage said cable and selective parts corresponding to a particular one of said stations and adapted 5 to properly co-act only with the switching device of the corresponding station, grip actuating means at said stations for engaging the grips of said carriers with the downwardly extending parts of said propelling means, and said auxiliary track at any given one of said stations extending substantially directly up to the main receiving track and being adapted to deliver a carrier, the grip of which has been engaged by said grip 10 actuating means with said part of the propelling means at said station, directly to the main receiving track even when said carrier has selective parts corresponding to another station, said auxiliary track engaging lugs remaining in engagement with the auxiliary track of said station substantially until the carrier is entered upon the main receiving track, said receiving main track having carrier guiding sections thereof extending in adjacency to the upper end of said auxiliary track and disposed substantially at the general level of said receiving main track, to guide through carriers, *en route* past said given station, thereover.

52. A store service apparatus comprising, in combination, main and supplemental tracks; a carrier propelling cable having a main portion for propelling the carrier along the main track and a looped portion 55 for propelling the carrier along the supplemental track; and means to interrupt and reestablish driving connection between the carrier and the main portion of the cable at opposite sides, respectively, of its looped portion.

53. A store service apparatus comprising, in combination, main and supplemental tracks; a carrier propelling cable having a main portion for propelling the carrier along the main track and a looped portion 45 for propelling the carrier along the supplemental track; and means automatically to interrupt and reestablish driving connection between the carrier and the main portion of the propelling cable at opposite 50 sides, respectively, of its looped portion.

54. A store service apparatus comprising, in combination, main and supplemental tracks; a carrier having cable-engaging means; a carrier propelling cable having a main portion for propelling the carrier along the main track and a looped portion 55 for propelling the carrier along the supplemental track; means to cause driving engagement of the carrier and the looped portion of the cable when the carrier is on the supplemental track; means to cause disengagement of the carrier from the main portion of the cable at one side of the looped portion when the carrier is traveling along 60 the main track; and means to cause reengagement of the carrier with the main portion of the cable at the other side of the looped portion.

In testimony whereof we have affixed our 70 signatures, in the presence of two witnesses.

GEORGE A. AMSDEN.
ROTHESAY P. KIDDER.
